Primary Examiner — Sandra Morris(74) Attorney, Agent, or Firm — Scully, Scott, Murphy & Presser, P.C.(57) CLAIM

The ornamental design for a proposition wagering card game, as shown and described.

DESCRIPTION

FIG. 1 is a front view of the table card game surface of the proposition wagering card game, showing my new design; and,

FIG. 2 is a front view of a second embodiment thereof. The broken line showing of the periphery is for illustrative purposes only, and forms no part of the claimed design.
